UNITED STATES PATENT OFFICE.

ARTHUR A. TAIT, OF WINNIPEG, MANITOBA, CANADA, ASSIGNOR TO THE BUSINESS SYSTEMS LIMITED, OF TORONTO, CANADA, A CORPORATION OF CANADA.

LOOSE-LEAF BINDER.

No. 872,388.

Specification of Letters Patent.

Patented Dec. 3, 1907.

Application filed June 19, 1906. Serial No. 322,384.

To all whom it may concern:

Be it known that I, ARTHUR A. TAIT, of the city of Winnipeg, in the Province of Manitoba, Canada, have invented certain new and useful Improvements in Loose-Leaf Binders; and I hereby declare that the following is a full, clear, and exact description of the same.

This invention relates to a loose leaf binder comprising a bottom board, two posts connected thereto, a top board adjustable on said posts relatively to the bottom board, and a spring actuated lock carried by the top board and arranged to engage said posts and prevent the outward movement of the top board until said lock is released, as hereinafter described and particularly set forth in the appended claims.

For a full understanding of the invention reference is to be had to the following description and to the accompanying drawings in which,

Figure 1 is a perspective view of the loose leaf binder showing the general construction and arrangement of the parts. Fig. 2 is a sectional view showing the locking bar in engagement with one of the posts. Fig. 3 is a similar view to Fig. 2 with the locking bar released from the post. Fig. 4 is a perspective view of the locking bar. Fig. 5 is a perspective view of the lock case. Fig. 6 is a perspective view of the actuating spring for the locking bar. Fig. 7 is a perspective view of the fulcrum for the locking bar, and Fig. 8 is a cross sectional view of one of the posts.

Like characters of reference refer to like parts throughout the specification and drawings.

Projecting from the inner surface of the bottom board *a* are two posts *b* located adjacent to the one edge *c* thereof. The posts *b* may be angular or multilateral in cross section, but it is preferable to make them triangular in cross section with the apex of each triangle pointing inwardly.

Opposed to the bottom board *a* is a top board *d* having apertures *e* for and preferably of the same shape as the posts *b* so that the top board can be adjusted relatively to the bottom board *a* and guided in its adjusting movements by the posts. Attached to the outer surface of the top board *d* is a metal plate *f* stiffened by a longitudinally disposed rib *g* and formed through

the metal plate *f* are apertures *h* corresponding to the apertures *e*. Connected to or forming part of the metal plate *f* is a lock case *i* inclosing the apertures *h*. The lock case *i* consists of side walls *j* and end walls *k* and *k'*. At the top of the end walls *k'* are inwardly extending flanges *l* having aperture sections *m* corresponding to the shape of the adjacent parts of the posts *b* and alined with the corresponding parts of the apertures *h*.

Contained within the lock cases *i* are locking bars *o* having down turned flanges *p* of substantially triangular shape, and extending through the flanges *p* and through the side walls *j* of the lock cases are fulcrum pins *q* upon which the locking bars *o* oscillate. The ends of the locking bars *o* adjacent to the posts *b* have aperture sections *r* corresponding in shape to the adjacent parts of the posts. When the locking bars *o* are in position in the lock cases *i*, the aperture sections *r* form with the aperture sections *m*, apertures corresponding in shape to the shape of the posts *b*, and the apertures so formed by the aperture sections *r* and *m* are alined with the apertures *e* and *h*. The ends *o'* of the locking bars *o* opposite the aperture sections *r* project beyond the flanges *p* and are slightly upturned to constitute thumb pieces 85 for the actuation of the locking bars. As shown in Figs. 2, 3 and 4, of the drawings, the dimensions of the locking bars *o* are slightly less than the inner dimensions of the lock cases *i*, so that the locking bars *o* can 90 freely operate therein, as hereinafter described.

Coiled on the fulcrum pins *q* are springs *s* having arms *t* and *t'*, which engage respectively the bottom of the lock cases *i* and the under surfaces of the locking bars *o*. As shown in Figs. 2, 3 and 4 of the drawings, the fulcrum pins *q* extend through the flanges *p* adjacent to the thumb pieces *o'*, but between the thumb pieces and the aperture sections *r*. 100

In manufacturing the binder, the top and bottom boards are made of the same shape and dimensions, and the metal plate *f* with the lock cases *i* are secured to the outer surface of the top board. The posts *b* are connected to the inner surface of the bottom board so as to extend through the alined apertures *e* in the top board and *h* in the metal plate and the aperture sections *m* and *r* in the top of the lock cases and locking bars. 110

In assembling the parts, the posts *b* are inserted through the apertures *e* and *h*, and when they come into contact with the locking bars they displace the latter as the top board moves on the posts towards the bottom board, the locking bars moving outwardly in the direction indicated by arrow in Fig. 3, to permit the top board sliding freely on the posts in the direction of the bottom board. When the top board contacts the inner surface of the bottom board or the adjacent surface of the leaves its movement towards the bottom board is arrested and its outward movement is prevented by the engagement of the locking bars against the posts. The locking bars are held in engagement with the posts by the action of the springs *s* which press the thumb pieces *o* outwardly and the apertured ends of the locking bars inwardly to enable the apertured ends to bind against the posts during the outward movement or attempted outward movement of the top board. To release the locking bars from their engagement with the posts, pressure is applied to the thumb pieces *o* in the direction indicated by arrow in Fig. 2 to depress the thumb pieces into the lock cases. The depression of the thumb pieces into the lock cases moves the locking bars from the position shown in Fig. 2, to that shown in Fig. 3, and when the locking bars are in the position shown in Fig. 3, the top board *d* can be freely moved outwards on the posts *b* and removed therefrom if necessary. When the pressure is removed from the thumb pieces *o*, the actuating springs *s* move the locking bars from the position shown in Fig. 3, to that shown in Fig. 2 to cause the apertured ends of the locking bars to engage with the posts *b*. As shown in Fig. 2, the locking bars *o* when in engagement with the posts *b* incline slightly above the top surfaces of the lock cases *i* and the length of the locking bars *o* from their places of contact with the posts *b* to the center of the fulcrum pins *q* is greater than the length of a line parallel with the top surfaces of the lock cases drawn from the centers of the fulcrum pins to the adjacent surfaces of the posts, so that the outward pressure of the top board will be resisted by a force equal to the strength of the parts.

Having thus fully described my invention what I claim as new and desire to secure by Letters Patent is:

55 1. A binder for loose leaves comprising, a

bottom board, multilateral posts projecting from the inner surface of the bottom board, a top board having apertures therein to receive the posts, a plate secured to the outer surface of the top board, having apertures *g* therein aligned with the apertures in the top board, lock cases secured to the plate each having upright sides and ends and a post engaging projection having its inner edge aligned with the corresponding edge of the aperture locking bars contained between the sides of the lock cases having their outer ends to be depressed within the lock cases and their inner ends to engage the sides of the posts and co-operate with the projections on the ends of the lock cases to prevent the outward movement of the cover, flanges extending downwardly from the locking bars, fulcrum pins inserted through the sides of the lock cases and flanges between the ends thereof, and springs mounted on the fulcrum pins to engage the bottom of the lock cases and the under surfaces of the locking bars adjacent to the outer ends thereof.

2. A binder for loose leaves comprising, a bottom board, multilateral posts projecting from the inner surface of the bottom board, a top board having apertures therein to receive the posts, a plate secured to the outer surface of the top board having apertures *g* therein aligned with the apertures in the top board, lock cases secured to the plate, each having upright sides and ends and a post engaging projection having its inner edge aligned with the corresponding edge of the aperture, locking bars contained between the sides of the lock cases having their outer ends to be depressed within the lock cases and their inner ends to engage the sides of the posts and co-operate with the projections on the ends of the lock cases to prevent the outward movement of the cover, triangular guiding flanges extending downwardly from the locking bars, fulcrum pins inserted through the sides of the lock cases and the flanges between the ends thereof, and springs mounted on the fulcrum pins to engage the bottom of the lock cases and the under surface of the locking bars adjacent to the outer ends thereof.

Winnipeg, May 26th, 1906.

ARTHUR A. TAIT.
